UNITED STATES PATENT OFFICE

NORMAN HERBERT SAUNDERS, OF HOMEWOOD, CLARENCE E. LOMAX, OF OAK PARK, AND THEODORE C. RIEBE, OF CHICAGO, ILLINOIS, ASSIGNORS TO RESERVE HOLDING COMPANY, OF KANSAS CITY, MISSOURI, A CORPORATION OF DELAWARE

TELEPHONE-STATION EQUIPMENT

Application filed December 22, 1927, Serial No. 241,746. Renewed May 2, 1929.

This invention relates to telephone systems in general, but is more particularly concerned with telephone substation and secretary service equipment.

5 In business offices and the like, various arrangements are employed whereby calls to the officials may be answered by their secretaries or stenographers from their own telephones, so that if the person called is not in his office at the time or is too busy to answer, his secretary or stenographer may inform the calling subscriber accordingly. One object of this invention is the production of new and improved telephone substations with secretary service equipment by which the secretary, after answering a call, may signal the wanted person to call him to his telephone and inform him of the nature of the call and who the calling subscriber is, without the calling subscriber being aware that this is being done, that is, without the calling subscriber hearing the conversation between the wanted subscriber and the secretary.

In large office buildings provided with 23 private automatic exchanges, certain officials in addition to having a line from the private automatic exchange sometimes desire to have direct access to a line to the central exchange. Another object of this invention is to provide 29 a telephone set in which two lines may terminate, a private automatic exchange line and a main exchange line, and from which a call over either line may be answered or may be initiated.

35 Another feature of the invention is that the arrangement may also be used as an inter-communicating system between one person and his stenographer, and may also be used for ordinary buzzer or signalling purposes.

40 These features, together with other features not specifically mentioned, and the operation of the equipment will be described in detail with the aid of the accompanying drawings comprising Figures 1 and 2. Figure 1 45 shows the circuit arrangement of the equipment and also the wiring between the different parts of the equipment. Figure 2 is a perspective of the key and cradle switch mechanism, showing three self-locking keys, 50 which are mounted on the desk stand (not

shown), and the unlocking arrangement controlled by the cradle switch, the invention being illustrated in connection with telephone sets of the cradle type.

In Figure 1, the telephone set and the associated equipment for the manager, for example, is shown between the two middle dotted vertical lines and includes a hand telephone comprising the receiver R and the transmitter T; a desk stand which includes 55 the dial D, induction coil I, condenser CC, self-locking keys K1, K2, K3, controlled by the cradle switch; and a bell box which houses the bells M, the bells P, the buzzer B, and the relay 50. The manager's main exchange telephone line terminates at the bell box terminals 1 and 2; his PAX telephone line terminates at the bell box terminals 3 and 4. Conductors 41' and 42' extending from terminals 6 and 7 to the PAX switchboard and are 60 connected to the exchange battery through 65 the impedance Y.

The secretary's telephone equipment is identical to the manager's telephone equipment, and the terminals of her bell box are 75 multiply connected to the corresponding terminals of the manager's bell box, with the exception of terminal 5.

The main exchange line terminates at the main automatic exchange in the individual 80 rotary lineswitch LS and is accessible thereat in the banks of local connectors such as connector C. The line extending to the PAX terminates in the rotary lineswitch LS' and is accessible thereat in the banks of local 85 connectors such as connector C'. This arrangement is shown for illustrative purposes only. Other possible arrangements include those in which the main exchange line passes through the PAX attendant's cabinet or terminates thereat in a jack, in which case the attendant has control of the completion of main exchange connections.

90 Before describing the operation of this equipment in detail, a description of the mechanical arrangement of the self-locking keys K1, K2, and K3 and the manner in which they are unlocked under the control of the cradle switch as shown in Fig. 2 will be described.

95 The cradle switch mechanism comprises a 100

lever 7 pivoted on the pin 6 and having two rollers 9, 9' attached to one end and having an L-shaped extension arm 7' to which a third roller 8 is attached. A control button 13 projecting through the center of the cradle 10 is fastened to the plunger 14 which is pivoted to the further end of the lever 7.

The self-locking key mechanism comprises the three keys K1, K2, K3, and the locking bar 2 which slides on the pins 15, 15', and has the three projections 5¹, 5², and 5³. One end of the locking bar is cut on a slant and bears against the roller 8 under the tension of spring 3. The keys K1, K2, K3, when deactuated are held in position under the tension of springs 16¹, 16², and a corresponding spring for key K³ (not shown).

The mechanism is shown in the position it assumes when the hand telephone 17 is removed from its cradle 10. In removing the hand telephone from its cradle, the lever 7 with its extension arm 7' is rotated to its alternative position shown by reason of rollers 9, 9' being forced under the tension of the cradle switch springs 11, 12, into the V-shaped recesses at the end of these springs. Since the locking bar 2 is maintained against the roller 8, it slides to the right to its locking position.

Now when any one of the keys, key K1, for example (which is shown operated) is depressed, the pin 4' fastened to the guiding plunger 18' of the key pushes the locking bar 2 to the left until the pin 4' slides past the projection 5' whereupon the locking bar 2 again slides back to its locking position. The key K1 is now locked in its operated position as shown by reason of pin 4' being held underneath projection 5'.

If now another key, such as key K2, is depressed, locking bar 2 is again moved to the left by pin 4². As a result, pin 4' of key K1 is allowed to slide past the end of the projection 5', permitting the key K' to be restored to its normal position under the tension of the spring 16'. Key K2, however, is now locked by reason of pin 4² being held underneath projection 5² as was key K1. In the same manner, if two keys are pressed simultaneously, both will be locked. Thus when any one or more keys are actuated, they are locked in position, and the key or keys previously operated are unlocked.

When the hand telephone is replaced in its cradle, the plunger 14 is forced downward causing the arm 7 with its projection 7' to rotate to its normal position. Roller 8 in moving upward slides the locking bar 2 to the left to its unlocking position, thereby unlocking such keys as may be locked. Rollers 9, 9', in moving upward, force springs 11 and 12 outward, thereby causing the separation of springs 12 and 11 from their working springs.

For the purpose of describing the general

operation of the equipment in detail, it will first be assumed that a call is extended from the main automatic exchange to the line comprising conductors 21 and 22 by way of the connector C. After connection thereto has been extended, ringing current is intermittently applied to the line conductors from the connector C in the ordinary way, which causes the ringing of the bells M at the manager's bell box and also the bells M' at the secretary's bell box. The manager need pay no attention to the ringing of his bells at this time. The secretary, to answer the call, removes her hand telephone from the cradle and, knowing that the call is from the main exchange by the distinctive sound of the bells M', presses key K12. Removing the hand telephone from the cradle allows springs 11' and 12' to close. Pressing key K12 causes springs 35' and 36' to disengage their resting contacts and engage their working contacts, thereby bridging the telephone set across the line conductors 21 and 22. This trips the ring in the connector C in the main automatic exchange, causing the connector C to complete the talking connection. The secretary now converses with the calling subscriber to learn the nature of the call and the identity of the calling subscriber.

If the manager is not in his office, the secretary, will, of course, so inform the calling subscriber. If the manager is in his office, the secretary will first speak with the manager. To do so, she presses both keys K11 and K13 simultaneously. These two keys lock, while key K12 is unlocked and restored. The operation of key K13 causes spring 37' to engage its working contact and thereby bridge resistance R11 across the line conductors 21 and 22 to maintain the connection with the calling subscriber intact. Pressing key K11 causes springs 33' and 34' to disengage their resting contacts and engage their working contacts, thereby bridging the secretary's telephone across the intercommunicating conductors 41 and 42 in series with relay 50'. Since conductors 41' and 42', across which the PAX battery is bridged in series with impedance Y, are connected to the intercommunicating conductors 41 and 42, a circuit is now closed for relay 50'. Relay 50' operates and at contacts 52' closes the circuit for buzzer B at the manager's desk, this circuit including conductors 41', 41, contacts 52', conductor 43, contacts 41', buzzer B, and conductor 42'. Buzzer B operates (buzzer B as well as buzzer B' being of the type in which the deactuation of the buzzer armature is brought about by the energization of a differential winding when the armature is attracted) and signals the manager. The manager upon hearing the buzzer B, removes his telephone from its cradle and operates key K1. These operations bridge his telephone across the communicating conduc-

tors 41 and 42 in series with relay 50. Relay 50 likewise operates and opens the circuit of the buzzer B by separating contacts 51.

The secretary and the manager may now 5 converse over conductors 41 and 42 without the calling subscriber hearing the conversation. The secretary informs the manager who it is that wishes to speak with him and what is wanted. If the chief informs the 10 secretary that he is too busy to answer the call at the time or does not desire to talk with the particular person calling, the secretary again depresses key K12 which operation unlocks keys K11 and K13 and allows them to restore, and again bridges the 15 secretary's telephone across conductors 21 and 22. She may then converse with the calling subscriber again and inform him that the manager is not available at this time.

20 If the manager desires to talk with the calling subscriber, however, he will depress key K2. Depressing key K2 unlocks key K1, and bridges his telephone set across the line conductors 21 and 22. The manager may now 25 talk with the calling subscriber.

After the secretary notes that the manager is conversing with the calling subscriber, she replaces her telephone in its cradle, which operation causes the separation of the springs 30 11' and 12' and also unlocks the key or keys operated at the time.

When the manager has finished conversation, he restores his telephone to its cradle causing the separation of springs 11 and 12 35 and the restoration of key K².

To answer a call coming in over the private branch exchange line comprising conductors 31 and 32, the secretary need only to remove her telephone from the cradle and 40 begin conversation, since the telephone conductors 23 and 24 are normally connected to the PAX line conductors 31 and 32, respectively. Again she may signal the manager, by depressing the key K11, (it being 45 unnecessary to depress key K13 in this case) and he may answer the secretary after depressing the key K1. If the manager wishes to converse with the calling subscriber on the private automatic exchange, the manager 50 need only press the cradle switch control button momentarily which unlocks key K1, after which his telephone is again bridged across the PAX line conductors 31 and 32. He may then commence conversation 55 with the calling PAX subscriber.

The arrangement may also be used as an intercommunicating system between the manager and his secretary. The manner in which the secretary may call the manager 60 has already been described, that is, she removes her telephone from the cradle rest and then depresses the key K11, which causes the buzzer B to operate and signal the manager. The manager, in the same manner may call the secretary by removing his tele-

phone from the cradle rest and operating key K1. This procedure causes the operation of relay 50 similar to manner in which relay 50' was operated and, assuming that the secretary has her telephone in its cradle, 75 closes the circuit for buzzer B' at the secretary's position at contacts 52. The secretary answers by removing her telephone from its cradle and operating key K11. Relay 50' operates and by separating contacts 51' opens the circuit of buzzer B'. Thus, either may signal the other by merely removing his telephone from its cradle and operating the key K1 or K11, as the case 80 may be, and as soon as the other person answers his buzzer stops signalling.

The manager as well as the secretary may make outgoing calls either to the main automatic exchange or to the private branch exchange. For example, should the secretary wish to extend a call to a subscriber served by the private automatic exchange, she merely removes her telephone from its cradle and dials the called number in the usual 85 way. The lineswitch LS' operates responsive to the removal of the telephone from its cradle, and selects an idle selector (not shown), and automatic switches in the private automatic exchange operate responsive to the digits dialled. To extend a call to the main 90 automatic exchange, the secretary removes her telephone from its cradle, then depresses key K12, thereby bridging her telephone set across the line conductor to the main automatic exchange, and then dials the 95 called number. Removing her telephone from its cradle of course in either case at first bridges the telephone across the private automatic exchange line conductors, and causes the operation of the lineswitch LS'. 100 When the secretary depresses the key K12, however, the telephone is removed from in bridge of these conductors and is bridged across the main exchange line conductors, causing the operation of the lineswitch LS' 105 in the main automatic exchange and the release of the lineswitch LS' in the private automatic exchange.

The manager may in like manner complete connections to the private automatic exchange or the main automatic exchange.

The invention has been illustrated in connection with lines from a main automatic exchange and from a private automatic exchange. The same equipment obviously may also be used in connection with lines from either a manual or automatic main exchange and either a private manual or automatic branch exchange, or may also be used in connection with two lines from one exchange, 115 it being desirable occasionally for a subscriber to have two separate lines. With this equipment of course only one telephone would be required.

A particular feature of the arrangement 120

- is that a second call coming in over one line may be answered by the secretary while the manager is conversing over the other line, or vice versa. Also, an outgoing call may be made over either line from either telephone while an incoming call over the other line is being answered from the other telephone.
- This completes the description of the invention. What is thought to be new and is desired to have protected by Letters Patent is specifically stated in the appended claims.
- What is claimed is:
1. In a telephone system, a main exchange line, a branch exchange line, and two telephones terminating said lines from either of which a call to either of said lines may be answered independent of any operation at the other telephone.
  2. In a telephone system, a main exchange line, a branch exchange line, two telephones terminating said lines from either of which a call to either of said lines may be answered independent of any operation at the other telephone, and means for establishing a talking connection between said telephones independent of either of said lines.
  3. In a telephone system, a main exchange line, a branch exchange line, two telephones terminating said lines from either of which a call to either of said lines may be answered independent of any operation at the other telephone, and from either of which one of two simultaneous calls to said lines may be answered while the other call is being answered from the other telephone.
  4. In a telephone system, two telephones, a pair of intercommunicating conductors, connecting means at each telephone for connecting it to said conductors, a signal at each telephone, a signalling conductor, and means at each telephone responsive to the operation of the connecting means at the telephone for closing an operating circuit for the signal at the other telephone including one of said intercommunicating conductors and said signalling conductor in series, providing the connecting means at the other telephone is not operated, and for interrupting the operating circuit for the signal at the first telephone, providing it has been closed responsive to the operation of the connecting means at the other telephone.
  5. In a telephone system, two telephones, a pair of intercommunicating conductors, a signal at each telephone, a signalling conductor, means at the first telephone operable at will for closing a circuit including one of said intercommunicating conductors and said signalling conductor in series to start the operation of the signal at the second telephone, connecting means for connecting the second telephone to said intercommunicating conductors, and means responsive to the operation of said connecting means for closing a circuit including one of said intercommunicating conductors and said signalling conductor in a series to start the operation of the signal at the first telephone providing said first means is not operated, and for stopping the operation of the signal at the second telephone providing its operation has been started by the operation of said first means.
  6. In a cradle-type telephone stand, a set of keys, a locking bar for locking said keys when operated, a lever pivoted between its ends, a control button for operating said lever, switch springs, a set of rollers mounted on said lever for controlling said switch springs, an extension arm integral with said lever, a roller mounted on said extension arm and adapted to roll over the end of said locking bar and move said bar laterally to unlock any actuated key when said lever is operated by said control button.
  7. In a telephone stand, a key, a locking bar for locking said key when the key is operated, switch springs, a lever, a cam mounted on one end of said lever and adapted to control said springs, means for operating said lever, an extension arm integral with said one end of the lever, and a cam mounted on said extension arm and adapted to move said locking bar to unlock said key when said lever is operated.
  8. In a hand type telephone stand, a key, means for locking said key when it is operated, switch springs for completing the talking circuit of the telephone, a lever for unlocking said key and for controlling said switch springs, and means for operating said lever when the telephone is placed on the stand.
  9. In a telephone system, a telephone stand, two lines terminating at said stand, a telephone normally connected to the first of said lines, a self-locking key for disconnecting said telephone from the first of said lines and connecting it to the second of said lines, signalling and talking circuits for said telephones, switch springs for controlling said circuits, and a switch button for controlling said switch springs and said key.
  10. A telephone set including a stand, a hand type telephone, a talking circuit control switch actuated by the telephone responsive to its being taken into use, a line connecting key, and a locking arrangement for said key controlled by said switch.
  11. A telephone set including a receiver normally adapted to rest on a supporting member when not in use, a line connecting key, a locking mechanism for said key, and arrangements whereby said locking mechanism is rendered effective responsive to the receiver being removed from the supporting member and disabled responsive to its replacement thereon.
  12. A telephone set including a receiver operated switch for completing the talking circuit.

circuit of the set, a plurality of manually operable keys, a common locking mechanism for said keys rendered effective to hold operated keys in that position by the operation of 5 said switch, and arrangements whereby a key locked in operated position may be released by the subsequent operation of another key and said other key locked in operated position.

10 13. A telephone set including a stand, a hand type telephone, a telephone operated talking circuit control switch, a plurality of keys, a common locking mechanism for said keys whereby any combination of the keys 15 may be simultaneously locked in operated positions, and mechanism for releasing said keys controlled by the switch.

14. A telephone set including a stand, a hand type telephone, a telephone operated 20 switch, a plurality of keys, a common locking mechanism for said keys controlled by the switch, and talking circuits controlled jointly by the switch and said keys.

15. In a telephone system, two subscribers' 25 lines, a substation telephone set terminating said lines, a plurality of keys associated with said set, means responsive to the operation of one of said keys for connecting one of said lines to said set, and means responsive to the 30 operation of another of said keys for connecting a holding bridge across said line, for disconnecting the line from the set, and for connecting the other of said lines to said set.

16. In a telephone system, a first subscriber's line, a second subscriber's line, a substation telephone set terminating said lines, means for connecting either line to the set, means for extending a connection via said first line, and means whereby said first line 40 is disconnected from the set and connected to a holding bridge responsive to the connection of said second line to the set.

17. In a telephone set including a receiver operated talking control switch, line connecting keys, a signal control key, and a common locking mechanism for said keys controlled by said switch.

In witness whereof, I hereunto subscribe my name this 19th day of December, A. D. 50 1927.

NORMAN HERBERT SAUNDERS.

In witness whereof, I hereunto subscribe my name this 19th day of December, A. D. 1927.

55 **CLARENCE E. LOMAX.**

In witness whereof, I hereunto subscribe my name this 19th day of December, A. D. 1927.

THEODORE C. RIEBE.
